United States Patent Office

Des. 193,768
Patented Oct. 9, 1962

193,768

DRAWER PULL

Cornell D. Hazenberg, Jamestown, N.Y., assignor to Chautauqua Hardware Corporation, Jamestown, N.Y.

Filed Aug. 19, 1960, Ser. No. 61,824

Term of patent 3½ years

(Cl. D10—8)

Fig. 1

Fig. 2

Fig. 3

FIG. 1 is a front plan view of a drawer pull, showing my new design;

FIG. 2 is a top plan view thereof;

FIG. 3 is an end view thereof.

I claim:

The ornamental design for a drawer pull, substantially as shown.
